UNITED STATES PATENT OFFICE.

ELWIN HOLBROOK ROONEY, OF PROVIDENCE, RHODE ISLAND.

COTTON-CLEANING MACHINE.

Application filed April 28, 1920. Serial No. 377,180.

To all whom it may concern:

Be it known that I, ELWIN H. ROONEY, a citizen of the United States, residing at Providence, in the county of Providence and State of Rhode Island, have invented new and useful Improvements in Cotton-Cleaning Machines, of which the following is a specification.

This invention relates to improvements in the construction and arrangement of mechanisms for the cleaning and carding of fibre particularly cotton, cotton waste or other vegetable fibre and relates more particularly to an improved means and method of transferring the stock from the cleaning cylinders of lickers-in or similar mechanisms. The improved features of my present invention are particularly valuable and advantageous when incorporated in the well-known type of licker-in mechanisms employed for the initial cleaning and carding of cotton fibre and is designed to effect the removal of the fibres from the licker-in cylinder by means of an air blast so as to eliminate the necessity of employing mechanical means therefor. My improved means is accordingly operative to remove the fibres in a manner avoiding the physical contact therewith of mechanical means thereby to eliminate and avoid the resulting damage to the fibre by the relatively severe mechanical action.

Important features of my invention consist of an improved means for directing an air blast or air jet tangentially of and on to the surface of the cylinder to be cleaned and further in the association therewith of suction condenser means suitably co-related with the blower so as to receive and convey the fibres dislodged by the blower. My improved arrangement materially contributes to the efficiency of the blower in its stripping action and further operates to loosen the trash and rearrange the fibre preparatory to further cleaning action by subsequent mechanisms. A still further valuable feature of my invention consists in an improved arrangement of the blower and suction means whereby a single blower is employed therefor connected at its intake and discharge sides or ports respectively with the suction and the blower conduits. This desirable arrangement is not only economical from the standpoint of instal-

lation and operation but is further advantageous in maintaining a definite and proper relation between the stripping blast and the suction co-related thereto. 55

Other valuable features and advantages of my improved arrangement will be understood by references to the accompanying drawings wherein like reference numerals are employed to indicate the corresponding parts in the several views. 60

In the drawings:— 65

Fig. 1 is a longitudinal side elevation illustrating the features of my invention with portions thereof shown in section so as to better illustrate certain parts.

Fig. 2 is a fragmental view in end elevation. 70

Fig. 3 is a diagrammatic view of my improved licker-in type of cleaning mechanism in an arrangement thereof adapted principally for the cleaning of cotton fibres, and 75

Fig. 4 is a similar view illustrating a desirable embodiment thereof in combination with a carding machine.

Fig. 5 is a longitudinal sectional view illustrating a desirable modified embodiment of the features of my invention. 80

Fig. 6 is a partial rear elevation thereof.

Fig. 7 is a view partially in longitudinal section illustrating further modified construction, and 85

Fig. 8 is a partial rear elevation thereof.

In the accompanying drawings I have illustrated the improved features of my present invention in a desirable arrangement incorporated in the usual licker-in type of cleaning machine which, as will be understood, may be independently used for the purpose of cleaning and straightening the cotton or other fibre or may be used in combination with a carding machine for the cleaning and carding of the cotton in a continuous operation to produce the usual sliver suitable for spinning into yarn. In the construction as shown, 1 indicates the usual supporting frame in which is suitably journaled the rotatable licker-in cylinder 2 having its peripheral surface provided with the teeth 3 to receive the fibre and carry the latter downwardly over the usual adjustable mote knives indicated at 5. 90

The stock is delivered to the licker-in over the usual feed plate 6 in the form of a lap from the usual lap roll not shown. The 100
105

stock is advanced over the feed plate by means of the rotatable feed roll 7 suitably journaled and operative to advance the stock over the nosing portion 8 of the feed 5 plate into contact with the teeth of the licker-in cylinder 2, the latter being rotated in the direction of the arrow by suitable driving connections. The licker-in cylinder receives the stock from the feed plate 6 10 with a combing action and carries it downwardly over the usual mote knives 5 which act thereon to extract the trash and foreign substances. The stock is then carried forward upon the licker-in cylinder to a 15 point beyond the usual licker-in protection screen 9 and is then stripped or removed from the licker-in cylinder in the manner as hereinafter described and is subjected to a further cleansing action and subsequent 20 combing and carding actions if desired.

In accordance with my present invention I have devised an improved pneumatic means and method of stripping the clean 25 fibre or stock from the licker-in cylinder which operates to effect the desired result in an efficient and improved manner having important advantages over the means and methods heretofore employed for that purpose.

As a further feature of my improved device my improved pneumatic stripping means is employed in conjunction with a suction condenser mechanism which cooperates therewith to loosen and rearrange the fibre and moreover to produce a further 35 cleaning action which is particularly effective in the removal of dust and small particles. The rearrangement and loosening of the fibres in my improved arrangement is particularly desirable in contributing to the 40 effectiveness of subsequent cleaning action upon the stock as will be readily understood.

A desirable construction embodying feature of my invention is here shown consisting of a cylindrical condenser cage 10 formed of a metallic screen or perforated cylinder which is suitably journaled upon the frame 1 and rotated by suitable driving 45 connections in a clock-wise direction as shown in Fig. 1. This cylindrical collecting screen or condensing cage has means associated therewith for creating a current of air therethrough and from that portion of the licker-in cylinder where the cotton is stripped therefrom so that the fibres are drawn by a current of air and deposited upon the surface of the condenser screen. For this purpose as here shown a curved 50 chute or conduit 12 is interposed between the licker-in cylinder 2 and the condenser cage 10 and arranged to provide a closed passage therebetween having a constricted opening 60 13 adjacent the surface of the licker-in cylinder to receive the stock therefrom and

having its walls at its rearward extremity in close contact with the periphery of the condenser cage. Within the condenser cage there is positioned a stationary slotted drum 15 extending longitudinally therethrough 70 and provided with an elongated slot 16 directed toward and in registration with the rearward open end of the chute 12 to establish communication therewith through the condenser screen. 75

As will be readily understood one end of the drum is suitably closed and at its opposite end as shown the drum is open ended and connected to communicate with a suction pipe 18. At its other or lower end the 80 suction pipe 18 is connected to the inlet port of a suitable rotary air pump or fan 20, the rotor 21 of which has affixed thereon a driving pulley 22 which is rotated at suitable speed by means of a driving belt 23. 85 From the discharge opening or port of the blower fan 20 a pipe 24 is vertically extended and terminates in a connection with a horizontally arranged blower 25 extending transversely of and in close proximity to the 90 peripheral surface of the licker-in. The blower 25 is provided with an elongated outlet slot or nozzle 26, which as illustrated is directed tangentially to the circumference of the licker-in cylinder 2 so as to direct a 95 blast of air into contact with the teeth thereof in a direction to dislodge and strip the fibres therefrom. As will be further noted the stripping blast from the nozzle 26 is also directed toward and into the forwardly directed opening 13 of the chute whereby the suction of the latter cooperates with the blast to raise the fibre and carry it into the transfer chute. 100

As indicated in Fig. 1 the wall 27 of the chute 12 is extended forwardly over the active portion of the air blast so as to insure that the latter and the fibre carried thereby enter into the passage way of the chute 12. As will be obvious from the construction 110 illustrated the fibres removed from the licker-in cylinder by the blower 26 will be drawn by the suction of the fan through the chute 12 and deposited upon the condenser cylinder 10 in the form of a layer or lap, the thickness of which is governed by the speed of rotation of the condenser cage and from the latter it passes beneath a condenser roll 28 and is stripped therefrom by 115 means of a suitable stripping knife or equivalent means to pass from the machine. 120

As will be readily appreciated the resulting operation of my improved mechanism effects the stripping or removal of the stock from the licker-in cylinder under the co-operating influence of the suction and blower or air blast whereby this function is performed in an efficient manner and without the employment of mechanical means to engage the fibres such as the strip- 125 130

ping brushes commonly employed. As a result the fibres are stripped from the licker-in without the more or less severe mechanical action and damage to the fibre resulting therefrom. Moreover in the approved construction of mechanism, as illustrated, a single fan or blower may be employed with economy to produce both the suction and the stripping blast with the advantage of maintaining a constant and proper ratio in the respective volumes thereof.

In addition to the main stripping blower 25 I may desirably also provide an auxiliary blower pipe 29 arranged at the opposite side of the entry opening to the chute 12 from that of the blower 26 and provided with a nozzle opening directed tangentially against the surface of the licker-in cylinder in opposed relation to the nozzle 26 to direct a reduced air current against the teeth of the cylinder to raise any fibre thereon and having the tendency to deflect the stripping currents upwardly into the chute 12. As will be understood this auxiliary blower should be of reduced volume or pressure relative to that of the main stripping blast from nozzle 26 and the air supplied therefor may be from any suitable source.

As will be readily appreciated the improved stripping blast of my invention is capable of use in modified form and arrangement without departing from the broader scope of the invention and is susceptible of use for the stripping of the fibre from the cleaning or carding cylinders of various types. Furthermore while I have described and illustrated in Fig. 1 a desirable construction of cleaning machine which may be used independently as a cleaning unit it will be understood that the improved features thereof may be employed in multiple units arranged in tandem relation where further cleaning action is desirable.

In Fig. 3 there is illustrated diagrammatically such an arrangement wherein the mechanism of Fig. 1 is duplicated in tandem arrangement to produce a double unit cleaning and combing mechanism.

Furthermore as shown in Fig. 4 my improved features and mechanism may be embodied in a tandem licker-in mechanism associated with a carding machine in an arrangement generally similar to that disclosed in patent to Beirne Gordon, jr. No. 1,165,088, issued under date of December 21, 1915. In the latter construction as indicated my improved mechanism as described is arranged in advance of a second licker-in cylinder 30 arranged to deliver the stock directly to the main carding cylinder 31 which is rotated in the direction as indicated to carry the stock under the usual flats 32 to be carded thereby. From the cylinder 31 the stock is received upon the doffer cyl-

inder 34 from which it is stripped by the usual stripper 35 and passed through the usual forming trumpet 36 from whence it is fed by the calender rolls 37-37 as a sliver to the coiler 38. The plural licker-in arrangement in combination with the carding machine as last described is particularly desirable in that the improved arrangement produces an initial cleaning of the fibre which contributes materially to the effectiveness of the succeeding cleansing action in the card proper whereby the necessity of double carding is eliminated. By the incorporation of my improved feature within the arrangement as described it will be noted that the fibres delivered to the card will be in a greatly improved condition not only as to parallelism and as to cleanliness but also as to the physical condition of the staple.

In Figures 5 and 6 I have illustrated a cleaning machine of the character described employing a modified form of pneumatically operating stripping means for removing the cotton from the licker-in cylinder. In its general features this machine, of Figures 5 and 6, is of a substantially similar construction to that of the machine illustrated in Figures 1 and 2 comprising the usual licker-in cylinder 2 operating with more knives 5 to which the stock is fed by means of the feed roller 7 from the usual feed plate 6. The fibre as removed from the licker-in cylinder passes through the chute 12 to the condenser cage or rotatable screen cylinder 10 from which it passes from the machine beneath the condenser roll 28. The construction embodies the stationary cylindrical baffle or drum 15 as hereinbefore described having a closed end and its opposite end being open to communicate with a suitable suction blower or fan, the rotor of which may desirably be mounted upon a shaft 40 provided with an external driving pulley 41 therefor. It is designed that rotation of the fan shall be in a direction to exhaust the air from within the drum 15 to create a continuous air current through the elongated opening 16 thereof so as to suck the fibre on to the condenser cylinder or screen 10 from within the chute 12.

The modification of Figures 5 and 6 consists in the provision of pneumatic stripping means for removing the fibre from the licker-in cylinder consisting of suitable blowers 43 and 44 provided with elongated outlet nozzles 45 and 46. These nozzles extend longitudinally of the peripheral surface of the licker-in cylinder and as indicated are directed tangentially against the surface of the cylinder in opposite directions whereby the air currents therefrom will meet and be deflected upwardly within the transfer chute 12 to convey the fibres therethrough. The blowers 43 and 44 are connected with con-

duits 48 and 49 to an air compressor or compressed air reservoir whereby in its modified form the stripping blast or air current is derived from a source independent 5 of the blower 21 of the condenser cage. As will be fully understood the blowers or blower nozzles 45 and 46 are wholly enclosed within the forward portion of the transfer chute 12.

10 In Figures 7 and 8 I have disclosed a further approved modified construction designed particularly to effect a more direct transfer of the stock from the licker-in cylinder to the condenser means. As indicated this arrangement comprises the usual licker-in cylinder 2 having the cooperating mote knives 5, plate 6 and feed rolls 7 and to cooperate therewith a double condenser cage is provided. The latter comprises 20 similar rotatable condenser screens 52 and 53 arranged one above the other and rotatable upon the respective shafts 54 and 55 through suitable driving connections not shown. Each of the condenser screen encloses a stationary cylindrical baffle or drum 57 or 58 suitably supported to extend longitudinally therethrough and provided with centrally and forwardly directed openings 60 and 61 facing toward the licker-in cylinder.

30 In the manner as hereinbefore described the baffles or drums are closed at one end and at the opposite end communicate with a conduit or pipe 63 providing a passage 35 way to the intake of a suitable suction blower 21 mounted upon an operating shaft 64 whereby the single blower will operate to exhaust the air from both of the baffle drums as is readily understood. A suitable 40 enclosure or covering for the licker-in and condenser cages is provided consisting of a top cover plate 66 having its forward and rearward end portions curved into close proximity to the surfaces of the licker-in 45 and upper condenser cage respectively and a bottom cover plate 67 is similarly arranged to form a bottom wall and to enclose the lower condenser screen. It will be further understood that at the opposite side 50 suitable side enclosing walls 68 are provided. Intermediate of the licker-in and uppermost condenser a suitably curved baffle 69 is positioned as indicated to lie in close proximity to the curved surfaces of the licker-in and condenser cage and to define 55 between its lower edge and the forward edge of the bottom plate 67 an opening or exposure of the licker-in surface directed toward the condenser and from which the 60 stock is removed in the manner as hereinbefore described. For this latter purpose a suitable blower pipe 70 is positioned as shown to extend axially of the licker-in cylinder and is provided with an elongated 65 nozzle 71 adjacent the lower portion of said

cylinder and directed tangentially thereagainst and toward the condenser cage openings. The discharge of air or air blast from the nozzle 71 will in this arrangement be operative to strip the fibre and project the 70 same directly on to the condenser screens. From the latter the stock will pass upwardly between the condenser rolls 72—73. As will be further understood the blower pipe 70 may be suitably connected to any source of 75 air supply, for instance to an external source of compressed air or as indicated in Figures 1 and 2 the air current may be supplied from the exhaust of the blower.

Having described my invention, I claim:— 80

1. In a machine of the character described, the combination of supporting frame, a rotatable licker-in cylinder suitably journaled therein and clothed upon its peripheral surface with picker teeth, means for feeding the stock to the cylinder, mote knives suitably arranged to coat with the cylinder for cleaning the fibre, a suction condenser arrangement associated with the licker-in cylinder and positioned relatively lower than 85 said cylinder and comprising a cylindrical collecting screen suitably journaled, a slotted drum positioned within the condenser screen, a transfer chute interposed between the licker-in cylinder and the condenser screen and having a forward opening communicating with a slot of the drum through the condenser screen adjacent the top portion thereof, a suction fan connected with the drum to exhaust the air therefrom and create a suction through the transfer chute to the condenser screen, said transfer chute at its forward end being provided with an entry opening in close proximity to the 90 licker-in cylinder and the air blower means 100 arranged to direct an air blast upon a peripheral surface of the licker-in cylinder and directed into the entry opening of said chute, a connection from said blower means communicating with the discharge port of 105 the fan whereby the latter produces both the suction and blower air currents, means for 110 rotating the licker-in cylinder, means operative to rotate the condenser screen and means for operating the blower fan, substantially as described. 115

2. In a machine of the character described, the combination of a cylinder having teeth upon its peripheral surface, means to deliver the stock thereto, means to coat with the cylinder to effect the cleaning of the fibre and means operative to transfer the fibre from said cylinder comprising means for directing an air blast substantially tangential to the circumference of said cylinder in the direction of rotation of said cylinder, a supplemental means for directing an air blast substantially tangential to the circumference of said cylinder and in opposed relation to said first air blast and suction means 120 125 130

cooperating therewith and having an entry opening toward which the air blasts are directed, substantially as described.

3. In a cleaning machine for cleaning cotton fibre and the like comprising a supporting frame, a rotatable licker-in cylinder suitably journaled therein and provided upon its peripheral surface with teeth, means to deliver the stock thereto, means to co-act with the cylinder to effect cleaning of the fibre, means to transfer the fibre from said cylinder comprising blower means for directing an air blast into contact with the fibres at the top of the cylinder, suction condenser means arranged to receive the fibre removed from the cylinder, and positioned at a lower level with relation thereto, a chute interposed between the cylinder and the suction condenser means, said chute having an entry opening disposed adjacent said top of the cylinder and arranged whereby the blower is directed thereinto, a suction fan associated with the condenser means to create a suction thereto and a connection from the discharge port of said fan to the blower for operating the latter, substantially as described.

4. In a machine of the character described, the combination of a cleaning cylinder, means to deliver the stock thereto, means to co-act with the cylinder to effect the cleaning of the fibre and means to transfer the fibre from said cylinder comprising means for directing air currents tangentially to the circumference of the cylinder into contact with the fibres and in opposed relation and a transfer chute having an entry opening into which the opposed air currents converge.

40 5. In a machine of the character described, the combination of a cylinder having teeth upon its peripheral surface, means to deliver stock thereto, means to co-act with the cylinder to effect the cleaning of the fibre and means operative to transfer the fibre from said cylinder comprising means for directing an air blast substantially tangential to the circumference of said cylinder in the direction of rotation thereof and a supplemental means for directing an air blast substantially tangential to the circumference of said cylinder and in opposed relation to said first air blast and of reduced volume and said air blasts being positioned to impinge upon the cylinder at substantially the top surface thereof.

50

tangential to the circumference of said cylinder and in opposed relation to said first air blast and of relatively reduced volume.

6. In a machine of the character described, the combination of a licker-in cylinder having teeth upon its peripheral surface, means to deliver the stock thereto, means to co-act with the cylinder to effect the cleaning of the fibre and means operative to transfer the fibre from said cylinder comprising means for directing an air blast substantially tangential to the circumference of said cylinder in the direction of rotation thereof and a supplemental means for directing an air blast substantially tangential to the circumference of said cylinder and in opposed relation to said first air blast and of reduced volume and said air blasts being positioned to impinge upon the cylinder at substantially the top surface thereof.

7. In a machine of the character described, the combination of a licker-in cylinder having teeth upon its peripheral surface, means to deliver the stock thereto, means to co-act with the cylinder to effect the cleaning of the fibre and means operative to transfer the fibre from said cylinder comprising means for directing an air blast substantially tangential to the circumference of said cylinder in the direction of rotation thereof and a supplemental means for directing an air blast substantially tangential to the circumference of said cylinder and in opposed relation to said first air blast and of reduced volume and said air blasts being positioned to impinge upon the cylinder at substantially the top surface thereof and suction condenser means cooperating therewith and positioned at a relatively lower level and a transfer chute provided with an entry opening into which the air blasts are directed and an outlet opening positioned to deliver the stock to the condenser means at the upper level thereof.

In testimony whereof I have signed my name to this specification.

ELWIN HOLBROOK ROONEY.
